UNITED STATES PATENT OFFICE.

JOHN L. MURDOCK, OF BOUND BROOK, NEW JERSEY.

SAFETY RAILWAY APPARATUS.

1,185,703.

Specification of Letters Patent.

Patented June 6, 1916.

Application filed June 11, 1915. Serial No. 33,443.

To all whom it may concern:

Be it known that I, JOHN L. MURDOCK, a citizen of the United States, and residing at Boundbrook, in the county of Middlesex and State of New Jersey, have invented certain new and useful Improvements in Safety Railway Apparatus, of which the following is a specification, such as will enable those skilled in the art to which it appertains to make and use the same.

This invention relates to safety railway apparatus, and the object thereof is to provide an improved apparatus of this class designed for use in connection with the ordinary semaphores employed in what are known as block system railways, and whereby a train of cars will be automatically brought to a stop if it enters a block in which there is another train; a further object being to provide an improved apparatus of the class specified part of which is connected with the locomotive of a train and part of which is placed between the rails of the track, and which also involves the use of said semaphores.

The invention is fully disclosed in the following specification, of which the accompanying drawings form a part, in which the separate parts of my improvement are designated by suitable reference characters in each of the views, and in which:

Figure 1 is a diagrammatic view showing parts of two rails of a railway track and with part of my improved safety apparatus that is placed between the rails of the track, part of the construction being broken away; Fig. 2 a partial section on the line 2—2 of Fig. 1 and on an enlarged scale; Fig. 3 a diagrammatic view showing the entire apparatus including that part thereof connected with the locomotive and that placed between the rails of the track; and, Fig. 4 a diagrammatic view showing the rails of the track, two semaphores, and indicating two locomotives on the block between the two semaphores.

In the drawing forming part of this specification, reference being made to Figs. 1 and 4, I have shown at *a* the rails of a railway track and in Fig. 4 I have shown two semaphores *b* and *b*² and have also indicated at *c* and *d* two locomotives on the block between the semaphores only the rear end portion of the locomotive *c* being indicated and, in the

practice of my invention, all the blocks of the track are provided with a complete electric circuit involving the rails of the blocks, a battery *e* and wires *e*² and *e*³ each of which are connected with one of the rails as shown at *e*⁴, and each block of the system or railway is provided with a similar circuit. I also form between the rails of the track and adjacent to each semaphore, a pit *f* having a bottom *f*² and a top or cover *f*³ and in which is placed that part of the apparatus hereinbefore referred to as being located between the rails, and which comprises a non-magnetic base *g* on one end of which is placed a yoke-shaped frame *g*² in the bottom portion of which is pivoted as shown at *g*³ a non-magnetic plate *g*⁴, with the front end portion of which is connected a permanent horseshoe magnet *h*. The yoke-shaped frame *g*² is also provided with a supplemental member *g*⁵ which ranges forwardly and upwardly and in the top portion of which is a bar magnet *g*⁶ on which is wound an electric coil *g*⁷, and on the back portion of the base is secured a yoke *i*, comprising a base *i*², a back plate *i*³ and a downwardly and forwardly inclined top plate *i*⁴, and the bottom plate *i*² and top plate *i*⁴ are connected by an arc-shaped core piece *i*⁵ on which are mounted two oppositely wound or opposing magnetic coils *j* and *j*², and the top coil *j*² normally rests on the plate *g*⁴.

The poles of the magnet *h* are provided with extension poles *k* which are secured on the inner sides of the side members of the frame *g*² at the top thereof and which extend above said frame members, and between which is placed a transverse plate *m* and wound on the extension poles *k* below the transverse plate *m* are release coils *k*² and the extension poles *k* extend through the top or cover of the pit *f* and between the rails of the track as indicated in Fig. 1. Secured to the base member *g* forwardly of the frame *g*² are two contact springs *n* and *n*². The contact spring *n*² is forwardly of *n* and shorter than the contact spring *n*, and said contact spring *n*, in the operation of the apparatus, is operated by the magnet *h*, by the transverse base portion thereof to throw it into contact with the spring *n*², as indicated in dotted lines in Fig. 2.

The locomotives *c* and *d* are provided on the bottom thereof with a spring-supported

metal plate o , indicated in Fig. 2 and preferably made of magnetic material and provided at its opposite sides with spring contact fingers o^2 below which are placed other contact devices o^3 also carried by the locomotive, and the contact devices o^3 are provided with circuit wires o^4 and o^5 , one of which connects with a battery o^6 with which is connected another wire o^7 , and the wires o^5 and o^7 are connected with a magnet p mounted on the throttle lever p^2 of the locomotive, and pivoted to said throttle lever is an armature p^3 which operates in connection with the magnet p , and the release bar p^4 of the lever p^2 is provided with a pin p^5 in connection with which the armature p^3 operates to raise said release bar when the circuit through the magnet p is completed and, otherwise than is herein described, the throttle lever p^2 operates, or is operated in the manner of other devices of this class to bring the engine to a stop.

In Fig. 3 of the drawing I have shown the wire e^3 connected with the coil j^2 and at r I have shown a wire connecting the coils j^2 and j , and at r^2 a wire which is connected with the coil j and the coil g^7 on the bar magnet g^6 , and the wire e^2 which is connected with the battery e is also connected with the coil g^7 . Connected with the wire r^2 is a branch wire r^3 which is connected with one of the release coils k^2 . The release coils being connected by a wire r^4 and a wire r^5 is connected with the other release coil and with the contact device n . A branch wire r^6 is connected with the wire e^2 and with the contact n^2 . The above wiring completes two circuits connected in parallel, and one current of one circuit passes through the battery, through the coils j and j^2 , the coil g^7 and back to the battery, while the current of the other circuit passes from the battery through the coils $j-j^2$, the release coils k^2 , the contacts $n-n^2$ and back to the battery. The object of the latter circuit is to insure the release of the magnet h from its extension poles k , when a block is clear and the circuit constituting the block complete, at which time the coil j^2 of the opposing coils $j-j^2$ rises, and the magnet h drops, and the method of winding the coils on the extension poles k serves to reverse the flow of magnetism through said poles and release the magnets h .

It will be understood that the wiring as shown and described in Fig. 3 is diagrammatic as the wire e^3 does not connect directly with the coil j^2 but with the rails a , the rails acting as conductors and a branch wire s is connected with one of the rails a at s^2 , then with the magnetic construction shown in Fig. 3 and back to the rails through a wire s^3 in which the semaphore is placed and the wires s and s^3 which are connected with the rails a are insulated from the wires e^3 and e^2 where they connect with the rails

as shown at s^4 , and as shown in Fig. 4 the semaphores $b-b^2$ are placed in the same circuit as the magnet construction referred to, but the latter is not absolutely necessary, the only essential feature being that the magnet h , or the extension poles k thereof be located at a predetermined point adjacent to the semaphores $b-b^2$ or the beginning or just before the beginning of the block and in the block circuits. 75

The operation will be readily understood from the foregoing description when taken in connection with the accompanying drawing and the following statement. The normal position of the magnet h is that shown in full lines in Fig. 2, in which position the circuit through the wire e^2 , coil g^7 , wire r^2 , coils $j-j^2$ and wire e^3 is complete and the arm of the semaphore b^2 is supposed to be down, and the block controlled by the semaphore b^2 is clear, said block being indicated at x in Fig. 4. If a train or locomotive now enters the block x it will pass the semaphore b^2 and magnet h due to the fact that the said block is clear, but immediately after the said train or locomotive passes the magnet h , the front wheels and axle of the locomotive will short-circuit the block which operation raises the arm of the semaphore b^2 in the usual manner and the magnet h will be raised into its dotted line position shown in Fig. 2 by the weight of the coil j^2 as hereinafter described. If now the train or locomotive above referred to still remains in the block x , or partially so, as indicated at c in Fig. 4, and another locomotive d enters the block x by reason of the engineer failing to see the semaphore set at danger, or for any other reasons, and passes over the extension poles k of the magnets h which form a magnetic field, the plate o on the train or locomotive passing over or through said field will be drawn downwardly as indicated in dotted lines in Fig. 3, and the contact between the contact devices o^2 and o^3 will be completed and the throttle lever p^2 released as hereinbefore described thereby stopping the train or locomotive. It will be understood that when the block is clear, the circuit is complete in said block and the circuit passes through the opposing magnetic coils j and j^2 and the coil g^7 , and the object of the coil g^7 and the bar magnet g^6 is to preserve or retain the magnetism in the magnet h in its normal position, or the position shown in full lines in Fig. 2, and in this position the magnet h is not in direct contact with the bar magnet g^6 as an air space is provided between the same thus providing a magnetic communication, and by means of this air space the magnet h will not be retained when the opposing magnetic coil j^2 drops by reason of the short-circuiting of the block which causes said magnet h to rise into a vertical position. From the dotted line position of 95

the coil j^2 and magnet h shown in Fig. 2 the action of the opposing magnetic coils $j-j^2$ will raise the coil j^2 from the plate g^4 and permit the magnet h to drop by gravity into its full line position, shown in said figure, and the coil j^2 is held in its raised position by the circuit through the coils $j-j^2$ but when said circuit is broken or short-circuited the weight of the coil j^2 raises the magnet h into a vertical position.

My invention is not limited to the use of semaphores in connection with the track, or the separate blocks thereof, nor to any other particular form of block signal device, nor is the invention limited to one pit for each block, or one magnetic device for producing a magnetic field in each block, nor to the use of semaphores or other signal devices at all, nor is the invention limited to the exact form, construction and arrangement of the magnet h and its connected parts, nor to the use of the throttle lever p^2 for stopping the engine or train and the magnet p may be used in connection with any suitable device for this purpose, including air-brake devices, nor is my invention limited to the release coils k^2 on the extension poles k , and while I have referred herein to locomotives and trains, it will be understood that where the word locomotive or locomotives are used separately, trains are understood as included, but my invention may be used in connection with single cars or locomotives passing over tracks having my improved safety apparatus in connection therewith, and changes in and modifications of these as well as other features of the construction herein shown and described may be made, within the scope of the appended claims, without departing from the spirit of my invention, or sacrificing its advantages; and it will also be understood that my improvement may be used in connection with any kind or class of railway involving what are known as the block system or systems.

Having fully described my invention what I claim as new and desire to secure by Letters Patent, is:—

1. A railway system comprising a plurality of blocks, each of said blocks forming a closed circuit in which is placed a magnetic device, said magnetic device being provided with extension poles and being normally supported in an inclined position and adapted to be raised to a vertical position and in coöperation with said extension poles when the block is short-circuited.

2. A railway system comprising a plurality of blocks, each of said blocks forming a closed circuit in which is placed a magnetic device consisting of a permanent horseshoe magnet, a bar magnet, extension poles for said permanent magnet and opposing magnetic coils for operating said permanent magnet, said permanent horseshoe magnet

being normally in communication with said bar magnet and adapted to be placed in co-operation with said extension poles.

3. A railway system comprising a plurality of blocks, each of said blocks forming a closed circuit in which is placed a magnetic device, consisting of a permanent horseshoe magnet, a bar magnet, extension poles for said permanent magnet and opposing magnetic coils, said permanent horseshoe magnet being normally in communication with said bar magnet and adapted to be placed in co-operation with said extension poles by means of said opposing magnetic coils.

4. A railway system comprising a plurality of blocks, each of said blocks forming a circuit in which is placed a magnetic device having a horseshoe magnet, said horseshoe magnet being normally supported in an inclined position and adapted to be raised to a vertical position when the block is short-circuited, and means for retaining the magnetism in said horseshoe magnet when in its normal or inclined position.

5. A railway system comprising a plurality of blocks, each of said blocks forming a circuit in which is placed a magnetic device having a horseshoe magnet, said magnet being provided with extension poles and being normally supported in an inclined position and adapted to be raised to a vertical position when the block is short-circuited, and means for insuring the release of said magnet from said extension poles.

6. A railway system comprising a plurality of blocks, each of said blocks forming a closed circuit in which is placed a magnetic device consisting of a horseshoe magnet, a bar magnet, extension poles for said horseshoe magnet and two opposing magnetic coils, said horseshoe magnet being normally in communication with said bar magnet and adapted to be placed in coöoperative relation with said extension poles by the movement of one of said opposing magnetic coils when the block is short-circuited.

7. A railway system comprising a plurality of blocks, each of said blocks forming a closed circuit in which is placed a magnetic device consisting of a horseshoe magnet, a bar magnet, extension poles for said horseshoe magnet and two opposing magnetic coils, said horseshoe magnet being normally in communication with said bar magnet and adapted to be placed in coöoperative relation with said extension poles by the movement of one of said opposing magnetic coils when the block is short-circuited, said horseshoe magnet and extension poles producing a magnetic field, and means for stopping a train or locomotive on entering said magnetic field.

8. A railway system comprising a plurality of blocks, each of said blocks forming a closed circuit in which is placed a mag-

netic device consisting of a horseshoe magnet, a bar magnet, extension poles for said horseshoe magnet and two opposing magnetic coils, said horseshoe magnet being normally in communication with said bar magnet and adapted to be placed in coöperative relation with said extension coils by the movement of one of said opposing magnetic coils when the block is short-circuited, and means for retaining the magnetism in said horseshoe magnet when in its normal position.

9. A railway system comprising a plurality of blocks, each of said blocks forming a closed circuit in which is placed a magnetic device consisting of a horseshoe magnet, a bar magnet, extension poles for said horseshoe magnet and two opposing magnetic coils, said horseshoe magnet being normally in communication with said bar magnet and adapted to be placed in coöperative relation with said extension poles by the movement of one of said opposing magnetic

coils when the block is short-circuited, means for retaining the magnetism in said horseshoe magnet when in its normal position, and means for insuring the release of said horseshoe magnet from said extension poles. 25

10. A railway system comprising a plurality of blocks, each of said blocks forming a circuit in which is placed a magnetic device, said magnetic device being movable into different positions and adapted to present a magnetic field in one of its positions, and means for retaining the magnetism of said magnetic device when in another position. 30

In testimony that I claim the foregoing as my invention I have signed my name in presence of the subscribing witnesses this 40 8th day of June 1915.

JOHN L. MURDOCK.
